Primary Examiner — Kevin Rudzinski*Assistant Examiner* — Paul Bohannon(74) *Attorney, Agent, or Firm* — Pauley Erickson & Kottis(57) **CLAIM**

The ornamental design for a lamp, as shown and described.

DESCRIPTION

FIG. 1 is a top view of a lamp, according to one preferred embodiment of the invention;

FIG. 2 is a bottom view of a lamp, as shown in FIG. 1;

FIG. 3 is a side view of the lamp, as shown in FIG. 1;

FIG. 4 is a front view of the lamp, as shown in FIG. 1; and,

FIG. 5 is a perspective view of a lamp, according to one embodiment of this invention.

The broken lines are provided for the purpose of illustrating portions of the lamp that form no part of the claimed design.

1 Claim, 5 Drawing Sheets(56)
